ACCOUNTING MACHINE

James W. Bryce, Glen Ridge, N. J., assignor to
 International Business Machines Corporation,
 New York, N. Y., a corporation of New York

Application December 3, 1935, Serial No. 52,643

5 Claims. (Cl. 234—5.8)

This invention relates to accounting devices and more particularly to machines for making perforated records under selective control of distantly located accounting machines; the perforated records to be used in tabulating or sorting or other machines for the making of reports.

In textile mills, it is customary to keep records of operations of the different looms by attaching counters to each machine and causing some part 10 of the loom to actuate the counter. In order to use the records thus produced, it is necessary to make systematic entries of the records of the different machines.

One object of the present invention is to devise a system whereby the operations of machines such as looms may be automatically recorded on counting or accumulating mechanisms located at the separate looms and connected to a central station to control the punching of record cards 20 to be used in tabulating machines.

Another object is to provide a system of this kind in which a plurality of counting devices located at several looms may be selectively connected to the record perforating machine at the central station to automatically control the 25 punching of the record card.

Another object is to devise means for restoring the selector devices associated with the counters at the looms to normal positions after they have 30 controlled the making of record cards.

Referring to the drawings wherein I have shown what I now consider to be the preferred form of my invention:

Fig. 1 is a sectional side elevation of a perforating machine for producing punched cards to control tabulating machines.

Fig. 2 is a similar view showing different parts of the mechanisms.

Fig. 3 is a sectional elevation of a counting device adapted to be mounted on a loom to record the operations thereof.

Fig. 4 is a detail of the counter showing means by which arbitrary data such as the machine number may be set up.

Fig. 5 is a detail of a card lever contact controlling device in the perforating machine.

Fig. 6 is a wiring diagram illustrating the operation of the perforating machine under control of the loom counters.

Fig. 7 is a timing diagram of the contact operating cams in the machine.

The perforating machine illustrated here is of the type disclosed in my pending application, Serial No. 27,634, filed June 21, 1935, now Patent No. 2,146,283, for Card punching machine, and

application Serial No. 685,379 of C. D. Lake, filed August 9, 1933, now Patent No. 2,032,805, for Perforating machine. In the present application, only so much of the perforating machine is shown as is necessary to a full and clear understanding of the invention.

In the drawings, the record cards 1 to be punched are stacked in a hopper 2 with a weight 3 holding them flat in position so that the lowermost card may be fed by a picker 4 toward the left where it is received between feed rollers 5, 5' and fed over the punch die 7 under a row of punches 8 to a second set of feed rollers 9, 9'. The card is fed under the punches intermittently, stopping for a moment at each horizontal row 15 of index positions so that the punches may operate to perforate the card and be restored. After the punching of the card is completed, it is then fed to the next sets of feed rollers 10, 10' and 11, 11'.

While between the feed rollers 10 and 11, the card stops long enough to be printed upon by the printing device 12 similar to the time stamp shown in patent to Jackson et al., No. 875,272 of December 31, 1907. This printing device is provided with a type belt 13 wound upon reels 14, 15 and may be fed from one reel to the other and around a positioning roller 16. With the card resting between the feed rollers 10 and 11 and directly over the type belt, the operation of the printing hammer 17 will cause the characters in printing position to be printed on the under side of the card which may be facing downwardly.

The card picker 4 is operated by a gear segment 18 adapted to rock on shaft 19 and is driven by a cam follower 20 operated by a cam 21 on a shaft 22. Shaft 22 is normally idle and has fixed thereon an arm 23 locked by the armature 24 and controlled by the card feed clutch magnet designated CFCM. Loosely mounted on the shaft 22 is a gear 25 fixed with respect to a clutch disk 26 having a notch 27 adapted to cooperate with the clutch arm 28. Gear 25 meshes with a pinion 29 fixed on shaft 30 with a gear 31. Gear 31 meshes with gear 32 fixed to the driving pulley 33 which is driven by a belt 34 from the motor M. Thus, while the motor M is running, the gear 25 is constantly in operation. Energization of the magnet CFCM will attract the locking armature 24 which will release the arm 23 and permit the clutch arm 28 to engage the notch in clutch disk 23 so that the gear 25 will cause the shaft 22 to rotate. The energization of the card feed clutch magnet may be momentary so that after the shaft 22 has turned one revolution 55

the latching pawl 24 will be in position to stop the arm 23 and effect declutching to stop the shaft 22. Thus, one card will be fed from the stack 1 whenever the card feed clutch magnet is energized.

The feeding of the card from the stack 1 carries it as we have seen into the feed rollers 5, 5'. The step by step operation of these rollers is effected through a Geneva stop motion device 35 driven from the pulley shaft 33' as more fully disclosed in my aforesaid copending application. The Geneva device 35 is mounted on a shaft 36 and drives a gear 37 meshing with gears 38, 39 which drive the gears 40, 41 to operate the feed rollers 5, 5' and 9, 9'. Also driven from the pulley shaft 33' is an oscillating arm 42 connected to a plate 43 pivoted at 44 and adapted to cooperate with latch members 45 associated with the row of punches 8, there being one latch member 45 to each punch 8 and one such punch to each column of index positions on the record card. A spring 46 normally holds the latch 45 away from the operating plate 43. Each latch 45 is connected by a link 47 to an armature 48 of a selecting magnet 49. Energization of this magnet moves the latch 45 into cooperation with the plate 43 so that as the latter moves downwardly, it will force the punch 8 through the record card. The timing is such that between the feeding steps of the card, the operating plate 43 moves downwardly and back to its upper normal position. Thus, if the latch 45 moves into cooperation with the plate, a corresponding punch 8 will be forced through the card and then withdrawn therefrom while the card is standing still.

After the card has been punched and reaches the rollers 10, 10', these rollers will feed the card to printing position. This is done by energization of magnet ECM (Fig. 2) which attracts its armature latch 50, releasing clutch arm 51 so that the clutch dog 52 will engage the notched clutch disk 53 fixed to a gear 54 which meshes with gear 39 and is therefore constantly turning step by step.

Disk 53 and gear 54 are loose on shaft 55 while the arm 51 is fixed to this shaft. When the clutch dog 52 engages a disk 53, the shaft is caused to rotate a single revolution after which the latch 50 removes the clutch dog 52 and locks the shaft in its normal position. Fixed to shaft 55 is a second gear similar to gear 54 meshing with gear 56 which drives the gears 57 and through an idler 58 also drives gears 59. Gears 57 and 59 are associated with the feed rollers 10, 10' and 11, 11'. The revolution of shaft 55 then causes the rollers 10 and 11 to feed the card into printing position where it stops. The clutch magnet ECM is again energized to feed the card from printing position into the receiving hopper 60.

The operation of the printing hammer 17 is effected by energization of the printing magnet or solenoid PM which rocks bell crank 61, moving link 62 to the left. This rocks arm 63 counterclockwise loosely on shaft 64. The spring actuated latch 65 carried on arm 63 will then rock arm 66 fixed on shaft 64 on which is also fixed arm 67. This rocks the arm 67 with the hammer 17 counterclockwise until the camming action of the stud 68 turns latch 65 about its pivot far enough to release the arm 66. The spring 69 then rocks arm 67 with printing hammer 17 downwardly until arm 67 strikes its limit stop 70. This stopping takes place before the hammer strikes the card to effect printing but the inertia

of the hammer carries it beyond this point to effect the printing blow, after which the spring 71 retracts the hammer to normal position.

Associated with the card supply hopper 2 is a card lever MCL adapted to be rocked downwardly when there are cards in the hopper to close the MCL contacts. After the last card has been fed from the hopper, the card lever will rock upwardly into a hole or depression in the lower face of the card weight 3 and permit contacts MCL to open. The purpose of these contacts will be understood in connection with the wiring diagram. Other card levers include a die card lever DCL which is provided with a lateral projection 73 (see Fig. 5). When the card is fed from the hopper to the punches and is passing through punching position, it will rock this lever to close the DCL contacts. After the card leaves the punching position and is being fed toward printing position, it rocks another card lever designated RCL. This will open the RCL contacts which are normally closed. When the card reaches printing position, it will rock a card lever PCL to close the PCL contacts and after the card leaves the printing position and is being fed to the receiving or eject pocket 60, it will rock card lever ECL to open the normally closed ECL contacts.

Associated with the punching machine as disclosed in Fig. 2 is a distributor device comprising a brush arm 74 cooperating with a common contact segment 75 and a plurality of individual contact segments 76. When the arm 74 rotates one of its brushes it will successively pass over the contacts 76 while the other moves over the common contacts 75. The brush arm is adapted to turn a half revolution for each card punching cycle of the machine. The brush arm is fixed with respect to a gear 77 meshing through gearing 78, 79 with gear 80 which meshes with a gear 81 fixed to gear 25 which as pointed out turns continuously while the motor M is in operation.

Also fixed on shaft 22 is a cam FC controlling contacts FC1. Soon after the shaft commences to rotate, the contacts close for a short period, after which they open and remain open throughout the remainder of the cycle.

Associated with gear 79 are cam disks CC which control contacts CC1 to CC4, operating them during the various machine cycles for one record card.

In the present case I have shown the recording device as an ordinary counter as distinguished from an accumulator or totalizer, although any type of recording mechanism may be employed. In Fig. 3, a counter 84 is shown as having counter wheels 85 carried on a common shaft 86 and adapted to be actuated by a pawl 87 carried on an arm 88 attached to a lever 89 fixed to shaft 90. Also fixed on this shaft is an operating arm 91 which may be connected to the machine whose operations are to be counted so that each operation of the machine will rock the arm 91 downwardly. This will raise the arm 88 and turn the counter wheel 85 one step. A locking pawl 92 is provided to hold the counter wheel 85 in position.

This device is more fully disclosed in U. S. Patent #1,228,315 issued May 29, 1917, to Goss. In the present instance, each counter wheel 85 has fixed thereto a gear 93 meshing with an idler 94 which, in turn, meshes with gear 95 loosely mounted on shaft 96 and fixed with respect to a brush carrier arm 97 carrying a pair of brushes 98. One of the brushes is in con-

tact with a common conductor segment 99 while the other is in contact with one of ten contact points 100. Each of these contact points represent one of the ten numerals from "0" to "9" and the brush 98 will engage the particular contact 100 representing the numeral corresponding to the setting of its counter wheel 85. In Fig. 4, an additional set of brushes 98 and corresponding contacts 100, etc., is shown. These particular brushes may be set manually by the operation of a disk 101 which may be reached by opening a door 102. The disk 101 is notched to cooperate with an impositive latch spring 103 to hold it in set position. These manually set brushes may be used to effect an arbitrary setting in the machine to represent the machine number or other data which is not to be controlled by the operation of the loom. When a reading is to be taken from the counter, the arbitrary setting as well as the data entered under control of the machine, will be taken to produce a perforated record. Thus, when a perforated record is made under control of the counter to show the operations performed by a particular machine, the number of the machine will also be punched in the record card.

Wiring diagram

In Fig. 6, the selector switch 104 is shown as having a plurality of common contact segments 105. Associated with each segment 105 is a plurality of individual contact points 106. A separate interconnecting brush arm 107 is adapted to wipe over each segment 105 and its associated contact points 106. The parts are shown in normal position with the brush arms 107 disengaged from the contact points 106. Rotation of the switch rod 104 one step will move all of the brush arms 107 into cooperation with the first contact point 106 in each order. Turning of the rod two steps will connect the brush arms to the second contact point 106 of each order and so forth.

Fig. 6 shows three sets or counters representing the counters of Figs. 3 and 4. These three counters are designated X, Y, and Z. All of the contact segments 99, 99' of counter X are connected by wires 108 to the first contact point 106, each segment 99, 99' being connected to the contact 106 in a different order. The contact segments 99, 99' of accumulator Y are connected to the second set of contact points 106, each segment 99 and 99' being connected to a contact point 106 of a different order. Similarly, the contact segments 99, 99' of counter Z are connected to the third-contact point 106 each segment being connected to a contact 106 of a different order. Thus turning of the switch rod 104 one step will connect all the brush arms 107 to the contact segments 99, 99' of counter X. Turning of the rod two steps will connect contact arms 107 to the segments 99, 99' of counter Y and turning of the rod three steps will make connection to counter Z. Additional counters may be connected through the other contacts 106. The contacts 100 of the read out device are separately connected by wires 109 to the several contact points 76 of the distributor device 74 carried by the perforating machine. As the perforating machine operates, feeding a record card step by step under the punches 8, the distributor arm 74 will operate synchronously so that, assuming that the row of nines on the card reach the punching position first, the distributor arm or brush 74 will con-

nect the contact point 76 representing the "9" position to the common segment 75. If the brushes 98 in the corresponding order in the particular counter happen to interconnect the nine contact point 100 with the common segment 99, a circuit will close through the punch magnet to cause operation of the particular punch to make the perforated entry in the record card.

If the brushes 98 rest at some other position, as for instance, interconnecting the value "5" contact 100 with the segment 99 then no connection will be made to the punch magnet for the particular order until the card has been fed so as to place the row of fives thereon under the row of punches and the brush arm 74 has also moved to connect the value "5" contact 76 to the segment 75. The circuit will then be closed at this point to effect punching of the value "5" in the particular column.

Each contact segment 105 of the selector switch 104 is connected by a wire 110 to a separate plug socket 111. These plug sockets may be connected as desired to similar plug sockets 112 associated with the punch magnets 49. If the record card is provided with 45 columns of index points, there will be 45 punch magnets 49 and the plug sockets 111 of which ten are shown representing the ten denominational counter orders that may be connected to any ten punch magnets so as to effect punching in the group of columns desired.

In order to operate the perforating machine, the switch 113 will be closed. This will connect the operating motor M to the source of supply 114 so that the motor will commence to operate and cause the constantly running portions of the machine to operate.

The operator will then depress the start key 122 to close contacts 123. This will close a circuit from the source 114 through wire 124, relay magnet A, contacts 123, normally closed contacts D4, back to the other side of the source through the ground. Relay magnet A then closes its contacts A1 so that when the start key is released the circuit will continue through contacts A1, normally closed card lever contacts RCL to the other side of the source.

The operator may then select the particular counter from which he wishes to take a reading to produce a perforated record. This is done by operating the dial 115 similar to a telephone dial. As the dial is rotated by the operator, the successive lugs 116 will rock the arm 117 to escape to the left thereof. After the dial has been released, it will return to its normal position and each segment 116 will now push the arm 117 to the right, thus opening contacts 118. These contacts will thus be opened a number of times corresponding to the position to which the dial is rotated. Also when the dial is operated, its arm 119 will permit contacts 120 to open and will close contacts 121. These contacts will remain in these changed positions until the dial again returns to its normal position.

While contacts 118 are closed, relay magnet B is energized from the line 124 through contacts A2, contacts 118, relay Z, back to the other side of the line. As the dial 115 returns to normal position after having been operated and opens contacts 118 each time a lug 116 passes the projection 117, the circuit through relay B is broken. When relay B is energized, upper contacts B1 are closed causing energization of delayed relay C from line 124 through relay C, contacts B1 to the other side of the line. Whenever contacts 118

open, breaking the circuit through relay B, upper contacts B1 open and lower contacts B1 close. Upper contacts C1 which are closed by relay C remain closed for a short period after upper contacts B1 open due to the slow action of relay C so that a circuit is closed from battery 125 through magnet J, wire 126, upper contacts C1, lower contacts B1 and back to the battery through the ground. This will raise the armature 127, lifting the actuating pawl 128 which cooperates with ratchet wheel 129.

Then as relay B is again energized breaking lower contacts B1 the circuit will be broken through magnet J and the circuit through relay 15 C will be reestablished before upper contacts C1 have been broken. When the circuit through magnet J is broken and the operating pawl 128 is restored by its spring it will turn the ratchet wheel 129 one step to rotate the shaft 104 of the 20 selecting switch. The selecting switch will thus be operated a number of steps corresponding to the number of times that the dial 115 opens contacts 118, so that if the dial is operated to its "3" 25 positions, the selector switch will be turned three steps to connect the counter Z which is the third counter, through the switch, to the punch magnets 49.

After the dial 115 and the selecting switch have come to rest and the machine has operated 30 through a complete cycle to perforate a record card, relay B will be deenergized and magnet C will permit upper contacts C1 to open and lower contacts C1 to close. This will establish a circuit from the battery 125 through magnet J, wire 126, 35 lower contacts C1, wire 130, contacts J1, wire 131, segment 105a, contact points 106a, all of which are interconnected and connected to the ground to permit the circuit to be completed to the other side of the battery. This will cause armature 127 40 to operate the pawl 128 and at the same time open contact J1. Then as the pawl actuates the ratchet 129 and contacts J1 close, the circuit will be reestablished. This continues as long as the switch arm 107a is passing over the interconnected contact points 106a. When this switch arm reaches its normal position, the circuit through the relay J will no longer be established 45 and the parts will come to rest so that the operator may now make another selection through the dial 115.

The signal lamp 131a is connected to the supply line 124 and through wire 132 to a segment 107b so that when the selector switch is operated 50 the lamp will light and remain lighted until the selector switch arm has passed over all of the interconnected contact points 106b and is in normal position ready for a new operation.

When the operator depresses the start key 122 and energizes relay magnet A, contacts A3 are 55 closed to light the signal lamp 131a. After the card feeding begins by the rotation of shaft 22 in Fig. 2 and cam FC closes a circuit through relay magnet F, contacts F4 are closed to continue the circuit to the lamp 131 after the contacts A3 are opened. The circuit through contacts F4 will be maintained as long as relay F is energized. This relay becomes deenergized 60 when the record card leaves the printing position and actuates the card lever ECL which 65 opens the circuit through the relay F and holding contacts F1. A set of contacts F5 controls a shunt circuit around the dial controlled contacts 118. After the operating cycle of the 70 machine starts and cards begin to feed, energizing relay F, this relay closes contacts F5. If the dial 75

is now operated to cause contacts 118 to open, the circuit through relay B remains closed through contacts F5 and the circuit through the selector switch magnet J cannot be closed to cause operation of this switch.

We have seen that when the operator begins to turn the dial 115, contacts 121 are closed immediately and contacts 120 open at the same time. The closure of contacts 121 as explained causes energization of relay magnet D and this, in turn, causes closure of contacts D2.

We have also seen that while cards are in the magazine 2, the magazine card lever MCL will close the MCL contacts so that after the dial has been released and returns to its normal position 15 opening contacts 121 and closing contacts 120, a circuit will be closed through the card feed clutch magnet CFCM as follows: from the line 124, magnet CFCM, contacts MCL, contacts 120, contacts F2 which are normally closed, contacts 20 D2, contacts CC1 normally closed, back to ground. Soon after the energization of the magnet CFCM causes the operating shaft 22 to commence to rotate, the energization of relay magnet F will open contacts F2 and break the circuit through the magnet CFCM so that after the shaft 25 has completed a revolution, it will be declutched and latched by the armature latch 24.

When a card is fed from the magazine 2 into 30 punching position below the punches 8, the operation of the die card lever DCL closes the DCL contacts. Then contacts CC2 become closed. This will complete the circuit through magnet ECM as follows: from line 124, contacts DCL, contacts CC2, magnet ECM back to ground. The 35 energization of magnet ECM as shown in Fig. 2 causes the feed rollers 10, 11 of Fig. 1 to operate 40 to feed the card into printing position after it has been completely punched and fed by rollers 9 to rollers 10. The cam contacts CC2 are timed 45 to open soon after the card feeding cycle starts and the circuit will be held through the magnet ECM through holding contacts 132.

Contacts CC3 are timed to open when the card is in printing position between feed rollers 10, 11. 45 This deenergizes magnet ECM so that the drive to the feed rollers will be declutched when the card is in proper position. When the card is fed into printing position, it will operate the printing clutch lever PCL to close the PCL contacts. This 50 will close the circuit through relay magnet H. Contacts F3 are closed due to the energization of relay F and contacts CC4 will be closed to complete a circuit through the printing magnet PM from line 124 through contacts PCL, contacts 55 CC4, contacts F3, magnet PM back to ground. The energization of magnet PM as shown in Fig. 1 operates the printing hammer 17 to print the date or other data on the card which has just 60 been punched.

The energization of relay H closes contacts H1 so that the circuit will be reestablished through the magnet ECM from line 124 through contacts H1, contacts D8, contacts CC2, magnet ECM back to ground. This will cause the clutch disk 53 to 65 engage the clutch dog 52 as soon as the notch in the disk reaches the dog and start the operation of the feed rollers 10, 11 to feed the card out from printing position.

When the card is fed from printing position 70 into the eject pocket 60, it will operate the eject card lever ECL. This will open the circuits through the relay magnets D and F. The deenergization of relay D will permit contacts D3 to open deenergizing magnet ECM so that the 75

feed rollers 10, 11 will stop. Contacts D4 will close so that depression of the start key 122 will again energize relay magnet A. Contacts D2 will open so that as contacts F2 close, the circuit will not be established through the card feed clutch magnet CFCM until the dial 115 has operated to reenergize relay D.

The deenergization of relay F will open contacts F4 so that the circuit will be broken through the signal lamp 131a as soon as the selecting switch 104 reaches its normal position breaking the partial circuit through wire 132. Contacts F5 will also open so that the operation of contacts 118 will permit relay B to become effective once more to render the magnet J operative.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a recording system with a plurality of counters adapted for operation by machines for controlling recording of the operations of the machines, the combination of a common record perforating device, means for emitting a variable number of distinct impulses, means under control of said impulses for selectively connecting one of said counters to the perforating device, means under control of the connected counter for operating said device to punch a record of the setting of the counter, and means under control of said connecting means for automatically initiating operation of said operating means after connection of the selected counter.

2. In a recording system with a plurality of counters adapted for operation by machines for controlling recording of the operations of the machines on record cards, the combination of a common card perforating device, means for emitting a variable number of separate impulses, means under control of said impulses for selectively connecting the counters to said perforating device to control recording operation, means under control of said emitting means for feeding said cards through said device in succession, one card for each recording operation, and means under control of the connected counter for oper-

ating said device to punch a record of the setting of the counter in a card.

3. In a recording system with a plurality of counters each with multidenominational counter elements adapted for operation by machines for controlling recording of the operations of the machines, the combination of a readout device positioned by each denomination element of each counter, a recording machine, a single, central, manually operated device for selectively connecting all the readout devices of any desired counter to said recording machine, means under control of the selected devices for conditioning said recording machine for operation, and means cooperating with said conditioning means for controlling the recording machine to record a multidenominational reading of the setting of the selected counter.

4. In a recording system with a plurality of counters adapted for control by machines for controlling recording of operations thereof on record cards, the combination of a common recording device, means associated with each counter for identifying the counters, means for selectively connecting one counter and the associated identifying means to said device, means under control of the connected counter and identifying means for operating said recording device to record the counter setting and identification on a card, and means under control of said connecting means for feeding said cards one at a time, one for each recording operation.

5. In a recording system with a plurality of counters adapted for control by machines for controlling recording of operations thereof on record cards, the combination of a common recording device, means associated with each counter for identifying the counters, means for selectively connecting one counter and the associated identifying means to said device, means under control of the connected counter and identifying means for operating said recording device to control recording of the counter setting and identification on one card, a time controlled recording means, means under control of said connecting means for operating said time recording means as an incident to the recording of each counter setting to make a record on the same card of the time that the counter record is made, and means under control of said connecting means for feeding one card for each related counter, identification and time record.

JAMES W. BRYCE.
